UNITED STATES PATENT OFFICE.

WILLIAM H. CALLAN, OF FRANKLIN, PENNSYLVANIA, ASSIGNOR TO CHICAGO PNEUMATIC TOOL COMPANY, OF CHICAGO, ILLINOIS, A CORPORATION OF NEW JERSEY.

UNLOADING MECHANISM FOR COMPRESSORS.

1,275,843.

Specification of Letters Patent. Patented Aug. 13, 1918.

Application filed January 4, 1916. Serial No. 70,116.

To all whom it may concern:

Be it known that I, WILLIAM H. CALLAN, a citizen of the United States, residing at Franklin, in the county of Venango, State 5 of Pennsylvania, have invented a new and useful Unloading Mechanism for Compressors, of which the following is a specification.

My invention consists of a novel unloading mechanism for compressors which may be automatically controlled in accordance with variations in the receiver pressure and which may be manually controlled when desired.

15 Other novel features of construction and advantage will more clearly hereinafter appear in the detailed description.

For the purpose of illustrating my invention, I have shown in the accompanying 20 drawings one form thereof which is at present preferred by me, since the same will give in practice satisfactory and reliable results, although it is to be understood that the various instrumentalities of which my invention 25 consists can be variously arranged and organized and that my invention is not limited to the precise arrangement and organization of these instrumentalities as herein shown and described.

30 Figure 1 represents a sectional elevation of an unloading mechanism for compressors embodying my invention.

Fig. 2 represents, on an enlarged scale, a sectional elevation of a portion of my device.

Fig. 3 represents a perspective portion of the unloading mechanism in detached position.

Fig. 4 represents a perspective view of a 40 handle employed to manually actuate the unloading means.

Similar numerals of reference indicate corresponding parts in the figures.

Referring to the drawings:

45 1 designates the piston cylinder of a fluid compressor, which is provided with a reciprocating piston 2, the piston rod of which is adapted to be actuated by any desired source of power. 4 designates the main air 50 inlet opening.

6 designates an air chamber formed in the wall of the compressor in the present instance and communicating by means of the ports 7 with the piston chamber 8 at one

end of the cylinder and communicating by 55 means of ports 9 with the other end of the cylinder chamber. The ports 7 and 9 may be controlled by any desired or conventional type of valve mechanism and for the purpose of illustration, I have shown a type of 60 valve which is well-known in the art under the name of "Simplat" valve. The different valve mechanisms which control the communication between the air chamber and the piston chamber are each constructed in 65 a similar manner and I will therefore describe in detail but one of such valve mechanisms.

Each valve cage comprises an apertured valve seat 10, through which extends a valve 70 stud 11 comprising a bolt which also passes through an upper apertured valve keeper 12, which is spaced from the disk 10.

These plates are secured in position by means of a nut 13 in threaded engagement 75 with the bolt 11. The apertured valve seat and valve keeper are provided with hubs or bosses through which the bolt 11 passes, and thereby a space is formed to permit the movement of valves 14, which latter consist 80 of annular plates spaced from each other to form the ports 15, said ports being in alignment with the apertures in the valve keeper 12. The valve keeper 12 is provided with any suitable guiding means for the valves. 85 The valve keeper 12 carries the volute springs 16, which normally tend to maintain the valve plates 14 in closed position. The valve seat 10 is provided with a peripheral seat 17 at its bottom which engages a shoulder 18 on the cylinder 1. The bolt 11 is provided with an upwardly extending post or stud 19 which is adapted to be received in the aperture 20 of a cylinder 21, see Fig. 3, which is exteriorly threaded at 22 in order that it may be screwed into the valve cover 23, which latter is secured to the cylinder by means of fastening devices 24. The cylinder 21 is provided with a lock nut 25 in order to maintain it in its adjusted position.

The cylinder 21 performs a double function, it being seen that when it is screwed into the valve cover it engages the valve stud 19 and holds the valve cage on its seat and 105 at the same time it provides a cylinder adapted to receive the piston 26. The forward end of the piston 26 is chambered and

slotted to permit the same to partially surround the central post 27 of the cylinder and such central post is connected with the main body of the cylinder by means of the offset 5 or brace member 28 preferably integral therewith, see Fig. 3. This member 28 forms a guide for the forward portions of the piston 26 which is longitudinally bisected at its forward portion, to form the flanges or 10 blades 29, as will be best understood by reference to Fig. 3. The flanges 29 of the piston abut against the valve lifter 30, which is guided on the valve stud 19 and is normally maintained in its raised position by means 15 of a spring 31 interposed between the nut 13 and the hub of the valve lifter 30. The valve lifter 30 has a flange extending forwardly from its hub portion and integral with a plate 32, which latter is provided with the 20 forwardly projecting portions 33, which are adapted to pass through the ports in the valve seat 10 in order to maintain the valve away from its seat. The piston 26 is provided with double cup leather washers 34, 25 which are secured in place by means of a washer 35 and a fastening device 36, such as for example a rivet. The piston 26 fits the piston chamber 37 in the cylinder 21 and the upper end of such piston chamber 37 30 is made air tight by means of a close fitting threaded cap 38 in threaded engagement with the cylinder 21. The cap 38 has its upper face recessed at 39, thereby adapting the same to receive the hub of a handle 40, 35 said hub being provided with a cam face 41, as best seen in Fig. 4. The hub of the handle 40 is apertured to provide for rotatably mounting it on the pipe 42 which latter is in threaded engagement with the cap in order 40 to provide for the admission of motive fluid into the piston chamber 37. The cam face 41 on the handle 40 is adapted to co-operate with the upper end of a plunger 43 which 45 extends through the cap 38 and whose lower end is adapted to contact with the washer 35 carried by the piston 26. The lower end of the plunger 43 is preferably enlarged. The pipe 42 is connected by means of a coupling 44 with a pipe 45 which communicates 50 with a chamber 46 formed in a valve 47, which may be of any desired or conventional type.

The coupling serves as one type of means 55 to retain the cam face 41 in its proper relation to the plunger or pin 43.

The valve 47 comprises a sectional casing 48 in which is located a valve 49 controlling communication between the chamber 46 and the chamber 50, which latter is in communication with the receiver by means of a conduit 51. 52 designates a plunger which contacts with the valve and between the plunger and a washer 53 is interposed a spring 54,

the tension of which may be varied by 60 proper actuation of an adjusting screw 55 which is locked in position by means of a nut 56.

In the automatic operation of my novel unloading mechanism, it will be seen that 70 when the receiver pressure reaches the desired point, the unloader operates. Motive fluid is admitted through a pipe 45 into a piston chamber 37, to advance its piston 26 and thereby the valve lifter 30. This causes 75 the valve 14 to be opened and held open until the receiver pressure has been reduced to a point at which the differential unloader valve moves against its upper seat thus 80 exhausting the fluid from pipe 45 and piston chamber 37. The spring 31 then forces the valve lifter and piston back into running position as seen at the left hand side of Fig. 1.

When it is desired to start a direct motor mounted compressor against pressure, the manually actuated feature is employed which operates as follows:—The levers 40 are manually operated to move them to the opening position, as seen at the right hand portion of Fig. 1. During this movement of the levers 40, the cams on their hubs or body move the plungers 41 against the ends of their respective pistons 26. These pistons cause the valve lifters to be moved inwardly to unseat the valves and hold them open so that the fluid instead of being compressed flows into and out of the piston chamber during the reciprocation of the piston. As soon as the compressor has reached its normal speed, the levers 40 are returned to the position seen in Fig. 2 and the compressing of the fluid is effected in the usual manner.

I provide means independent of the receiver pressure to manually actuate the 105 valves which control the communication between the air inlet and each end of the piston chamber, so that when the valves are operated manually, they are moved by a direct and positive connection between the 110 actuating levers and their respective pistons.

In accordance with my present invention, I provide a single unit of simplified and 115 compact construction which may be operated either automatically or manually.

It will now be apparent that I have devised a novel and useful unloading mechanism for compressors, which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit 125

or scope of the invention or sacrificing any of its advantages.

Having thus described my invention, what I claim as new and desire to secure by Letters Patent, is:—

1. Unloading mechanism for compressors, comprising the combination with the valves controlling communication between the piston chamber and air inlet of the compressor, of valve lifters to actuate said valves, pistons to actuate said valve lifters, plungers contacting with said pistons, and means to actuate said plungers.
- 10 2. Unloading mechanism for compressors, comprising the combination with the valves controlling communication between the piston chamber and air inlet of the compressor, of valve lifters to actuate said valves, pistons to actuate said valve lifters, plungers contacting with said pistons, and manually controlled cams to actuate said plungers.
- 15 3. Unloading mechanism for compressors, comprising the combination with valve mechanism controlling communication between the piston chamber and air inlet of the compressor, of a cylinder securing said valve mechanism in assembled position and provided with a piston chamber, a piston in said piston chamber and operatively connected with said valve to actuate it, and means to introduce motive fluid into said piston chamber to actuate said piston.
- 20 4. Unloading mechanism for compressors, comprising in combination with the receiver and valve mechanism controlling communication between the piston chamber and air
- 25 inlet of the compressor, of a cylinder for securing said valve mechanism in position, a piston in said cylinder, said cylinder and piston having means common to them to prevent rotation of the piston, a valve lifter 40 actuated by said piston, means controlled by the receiver pressure to actuate said piston, and manually actuated means to move said piston to actuate the valve lifter.
- 30 5. Unloading mechanism for compressors, comprising in combination with valve mechanism controlling communication between the compression chamber and air inlet of the compressor, of a cylinder having an extension contacting with said valve mechanism 45 to fix it in position, a valve lifter to actuate the valve of the valve mechanism, a piston within said cylinder and guided by said extension, resilient means to retain the valve lifter in operative engagement with said piston, and means to effect the movement of said piston.
- 35 6. Unloading mechanism for compressors, comprising the combination with the receiver and the valves controlling communication between the piston chamber and air 50 inlet of the compressor, of a valve lifter to open said valves, pistons to actuate said valve lifters, means to automatically actuate said pistons, plungers to contact with 55 said pistons, and levers to actuate said plungers.
